FOLDING BOX

Isaac M. Rudowitz, New York, N. Y.

Application November 27, 1936, Serial No. 113,054

5 Claims. (Cl. 229—23)

This invention relates to folding boxes, more particularly to boxes of that type constructed from cardboard or other suitable light material.

The essential objects of the invention are to provide in a manner as hereinafter set forth, a folding box which is simple in its construction and arrangement, capable of being folded in a compact manner when not in use, durable, designed primarily for efficiently storing, transporting and protecting headgear for women, conveniently extended for the reception of the article to be positioned therein, and inexpensive to manufacture.

To the above ends essentially and to others which may hereinafter appear, the invention consists of the novel construction, combination and arrangement of parts as will be more specifically described and are as illustrated in the accompanying drawings wherein embodiments of the invention are shown, but it is to be understood that changes, variations and modifications may be resorted to which fall within the scope of the invention as claimed.

In the drawings:—

25 Figure 1 is a perspective view of a folded box in accordance with this invention and with the box extended and opened.

Figure 2 is a vertical sectional view of the box when extended and closed,

30 Figure 3 is a section on line 3—3, Figure 4.

Figure 4 is a section on line 4—4, Figure 2.

Figure 5 is a plan view, partly broken away, of the blank from which the body portion of the box is set up,

35 Figure 6 is a vertical sectional view of a modified form with the box extended and closed,

Figure 7 is an inverted plan view of the box shown in Figure 6.

Figure 8 is a plan of the blank from which 40 the body portion of the box shown in Figures 6 and 7 is set up,

Figure 9 is a perspective view of still another modified form of box when extended and opened,

45 Figure 10 is a transverse sectional view of the form of box shown in Figure 9 and with the box extended and closed,

Figure 11 is a section on line 11—11, Figure 9.

Figure 12 is an inverted plan of the box structure shown in Figure 10,

50 Figure 13 is a section on line 13—13, Figure 10.

Figure 14 is a section on line 14—14, Figure 10.

Figure 15 is a plan view of the blank from which the body portion of the box shown in Figure 9 is set up,

Figure 16 is a perspective view of still another modified form of box extended and opened,

5 Figure 17 is a transverse sectional view of the box shown in Figure 16 when the box is closed and extended,

Figure 18 is a section on line 18—18, Figure 16.

Figure 19 is an inverted plan of the box shown in Figure 17,

10 Figure 20 is a plan view of the bottom section forming an element of the box shown in Figure 16,

Figure 21 is a plan view of the blank from which the body portion of the box shown in Figure 16 is set up,

15 Figure 22 is a perspective view of still another modified form of box extended and opened,

Figure 23 is a transverse sectional view of the form of box shown when opened and extended,

20 Figure 24 is an inverted plan of the box shown in Figure 22,

Figure 25 is a plan view of a bottom section of the box shown in Figure 22, and

25 Figure 26 is a plan view of the blank from which the body portion of the box shown in Figure 22 is set up.

Referring to Figures 1 to 4, the box includes a foldable body section 1 and a foldable bottom section 2. The section 1 is formed of the walls 3, 4, 5 and 6. The latter at one side is provided with an upstanding inwardly extending flap 7.

30 Each of said walls at its bottom is provided with a horizontally disposed inwardly extending flap 8. The walls 4, 6 at their tops have oppositely foldable hinged rectangular flaps 9, 10 respectively.

35 The walls 5, 3 at their tops have oppositely foldable hinged lid sections 11, 12 respectively of like length and each of a length greater than the width of a wall 4 or 6. The outer end edges of the lid sections 11, 12 are indicated at 13, 14 respectively. The lid section 11 is formed with a pair of spaced endwise aligned oppositely 40 extending transverse slits 15 opening at its side edges 16 and positioned in proximity to end edge 13.

The lid section 12 is formed with a pair of oppositely extending spaced endwise aligned 45 transverse slits 17 opening at its side edges 18 and positioned adjacent end edge 14. The distance between the slits 17 and end edge 14 is

greater than the distance between the slits 15 and end edge 13. The portions of lid section 11 50 between the slits 15 and end edge 13 form bendable parts 19 for a purpose to be referred to.

The portions of lid section 12 between the slits 17 and end edge 14 provide bendable parts 20 55 for a purpose to be referred to.

The walls 3, 4, 5 and 6 merge into each other. The wall 6 merges into the flap 7. At the points of mergence of the walls into each other and the point of mergence of wall 6 with flap 7 bends 21 are formed. The flaps 8, 10 merge into the upper ends of the walls 4, 6 and at such points of mergence bends 22 are formed. The inner ends of the lid sections merge into the upper ends of walls 3, 5 and at such points of mergence bends 23 are provided. The bends 23 constitute a hinge means between the lid sections and the walls 3, 5. The flap 7 of the wall 6 is adapted to have its outer face secured to the inner face of wall 3 by a cementitious material whereby body section 1 will be set up as in a manner shown in Figure 1. To provide for body section 1 being folded upon itself it is formed with a pair of oppositely extending diagonal bends 24, 25 formed in the walls 6 and 4 respectively, and also in the flaps 10 and 8 respectively. The bends 24, 25 extend from opposite lower corners of the walls 6, 4 respectively to a point inwardly adjacent opposite corners of said walls 6, 4 respectively and through the flaps 10, 8 respectively adjacent opposite ends of such flaps.

The bottom section 2 consists of a flat member 26 which is mounted upon the flaps 8 which extend inwardly from the walls 3 to 6 inclusive. The member 26 is secured to the flaps 8 by suitable cementitious material and the member 26 not only provides the bottom of the box but also acts as a bracing means for maintaining body section 1 extended. The member 26 is provided with a diagonal bend 26a upon which it can be folded. The bend 26a extends from one corner of member 26 to another corner diagonally of the first-mentioned corner. The bend 26a coacts with the bends 24, 25 for the purpose of folding the box when desired.

When the box is closed a part of lid section 11 is superposed upon a part of lid section 12. Lid section 12 is first folded to seat on the flaps 8, 10, these latter being in the position as shown in Figure 1. After lid section 12 has been folded in the manner as stated the parts 20 thereof are bent inwardly and positioned under the flaps 8, 10. After lid section 12 has been folded to extend upon lid section 11 the parts 19 are bent inwardly to extend between the flaps 8, 10 and the parts 20 thereby the lid sections are detachably connected together. The parts 19 are of less length than the parts 20 and the position in which said parts 19 and 20 assume when the lid sections are detachably connected together appear in Figures 3 and 4.

With reference to Figure 5, a blank is illustrated from which body section 1 is set up. The blank 27 is formed from a suitable web of cardboard having parts thereof indicated at 28, 29, 30, 31 and 32 constituting respectively an oblong side part forming flap 7; a rectangular part forming the wall 6 and flap 10; a rectangular portion forming the wall 5 and lid section 11; a rectangular part providing the wall 4 and flap 8; and a rectangular portion forming the wall 3 and lid section 12. The parts 28, 29, 30, 31 and 32 have upper and lower ends. The parts 29, 31 are arranged in spaced relation. The parts 28, 32 are arranged in spaced relation. The part 28 is of less width and length than that of any of the said other parts. The part 28 merges into the part 29; the latter merges into part 30; the latter merges into the part 31 and the latter merges into part 32. The part 28 provides the flap 7 and at the mergence of such part 28 with part 29 the

blank 27 is formed with a lengthwise score 33 which provides the bend 21. The part 28 is at one end of the blank 27. The latter is formed with a pair of spaced parallel horizontal scores 34, 35 horizontally thereof and which extend from the ends of the score 33 to the side edge 36 of the blank 27. The blank 27 is also provided with a series of spaced parallel lengthwise extending disposed scores 37, 38 and 39 which are disposed in parallelism to the score 33 and extend from the score 34 to the score 35.

The parts 29, 31 are of like form and of the same width and length. The parts 30, 32 are of the same length and of greater length than the parts 28, 31. The width of parts 30, 32 corresponds to the width of parts 28, 31. The upper end of the blank 27 is formed with edge portions 40, 41, 42 and 43. The edge portions 41, 43 extend beyond the edge portions 40, 42. The lower end of the blank 27 is formed with V-shaped cutouts 44 to provide the edge portions 45, 46, 47 and 48 which are arranged in endwise opposed relation. The blank 27 is formed with spaced parallel slits 49, 50 extending inwardly from the inner end of edge portion 40 and inwardly from the ends of edge portion 42. The insetting of the edge portion 42 relative to the edge portions 41, 43 provides edge portions 52, 53, 54 which terminate at the score 34. The part 30 is oppositely slitted in proximity to edge portion 41 to provide the slits 55. The part 32 is oppositely slitted inwardly adjacent edge portion 43 to provide the slits 56. The other side edge of the blank 27 consists of an edge portion 55 and an edge portion 56 which is inset with respect to the portion 55, thereby providing an edge portion 57 which endwise aligns with the score 34. That lower end of the blank 27 formed with the V-shape cutouts also includes an inclined edge portion 58 and a straight edge portion 59 inset relative to the portion 55 and disposed in parallel relation to the edge portion 57. The edge portion 59 endwise aligns with the score 35.

The score 34 is arranged a shorter distance from the edge portions 40, 42 than from the edge portions 41, 43. The parts of the blank 27 between the score 34 and edge portions 40, 42 provide the flaps 8, 10. The part of the blank 27 between the score 34 and the edge portions 40, 42 forms the lid sections 11, 12. The parts of the blank 27 between the score 35 and the edge portions 45, 48 form the flaps 8. The score 35 provides the bends 60 between the flaps 8 and the walls 3 to 6. The parts of the blank 27 between the scores 33, 37, 38, 39, 34 and 35 form the walls 3 to 6 inclusive. The scores 37, 38, 39 provide the bends 21 between the walls 3 to 6 inclusive. The score 34 forms the bends 22 and 23. The parts 29 and 31 are formed with diagonally extending scores 61, 62 which provide the bends 24, 25.

Referring to Figures 6 and 7 they show a modified form of the box indicated at 63 which is of a similar construction to that of box shown in Figure 1 with the exception to be referred to. The box 63 shown in Figure 7 consists of a body section 64, a bottom section 65 and a set of couplers 66. The body section 64 is of the same form as the body section 1 with this exception that the flaps 8 are not included and in this connection it will be stated that the couplers 66 are substituted for the flaps 8. The couplers 66 are bendable strips of suitable material provided on one face with cementitious material. The couplers 66 are secured to the outer face of the walls of section 75

64 and to the lower face of the section 65. Otherwise than that as stated the box 63 will correspond to the box in Figure 1.

Figure 8 discloses a blank 67 from which the body section 64 is set up. The blank 67 is substantially of the same form as the blank 27 with this exception that it does not include the parts of blank 27 which provide the flaps 7 and it further does not include the score 35 of blank 27. 10 Otherwise than that as stated, the form of blank 67 is the same as blank 27 and it is thought unnecessary to specifically describe blank 67.

Referring to Figures 9 to 14 which disclose a modified form of folding box 68 in accordance 15 with this invention, the box consists of a body section 69 and a bottom section 70 secured together. The section 69 includes upstanding walls 71, 72, 73 and 74 and each of which has its bottom formed with an inwardly extending flap 75. The 20 walls 71, 73 are formed with top edges 76, 77 respectively which incline downwardly in opposite directions from the transverse centers thereof. The top edge 76 of wall 71 is formed with a pair of inwardly extending spaced flaps 78, 79. The 25 top edge 77 of wall 73 is formed with a pair of inwardly extending spaced flaps 80, 81. The flaps of each pair are disposed at opposite downward inclinations with respect to each other. The top edges of the walls 72, 74 are indicated at 82, 83 30 respectively and are straight.

The top edge 82 of wall 72 is provided with a lid section 84 formed with an inwardly extending flap 85 and a pair of spaced endwise aligning oppositely disposed slits 86, 87 adjacent the flap 85 and 35 with a pair of oppositely extending endwise aligned slits 88, 89 disposed in spaced parallelism to the slits 86, 87 respectively and formed at the points of emergence of the flap 85 with the lid section 84. The top edge 83 of the wall 74 has extending therefrom a lid section 90 formed with an inwardly extending flap 91. The body section 69 is provided with a pair of diagonal oppositely extending bends 92, 93. The bend 92 is formed in the wall 71 and the flap 79. The bend 93 is formed in the wall 73 and the flap 80. The bends 40 92, 93 permit of the body section 69 being folded upon itself. The body section 69 is provided with an upstanding flap 94 which extends inwardly from the wall 71 and is secured by cementitious material to the inner face of wall 72. The body section 69 is formed from a single web of material, such as cardboard.

The bottom section 70 consists of a panel 95 of any suitable material, such as cardboard and 55 which conforms in contour to that of the bottom of the body section 69. The panel 95 is mounted upon and secured by suitable cementitious material to the flaps 75. The panel 95 is provided with a diagonally disposed bend 96 to permit of the section 70 folding upon itself when the section 69 is folded upon itself. When the box is set up and the lid sections 84, 90 arranged in close position, the said sections will be folded to the position shown in Figure 10 and the flaps 85, 60 91 pass downwardly through the opening 97 provided between the flaps 78, 79 and through the opening 98 formed between the flaps 80, 81. The part of the lid section 84 between the slits 86 and 88 and indicated at 99 is bent under the flap 79 65 and the part of lid section 90 between the slits 87, 89 and indicated at 100 is bent downwardly to a position below the flap 81. By this arrangement the lid sections are detachably secured in close position.

75 With reference to Figure 15 it discloses a blank

101 from which the body section 69 is set up. The blank 101 is formed from a single length of suitable material, such as cardboard having one of its lengthwise edges formed with edge portions 102, 103, 104, 105, 106, 107, 108, 109 and 110. The edge portions 102 to 105 and 107 to 109 are arranged inwardly of the edge portions 106, 110. The edge portion 102 is arranged inwardly of the edge portions 103, 104 and 107 to 109. The edge portions 104, 108 are arranged forwardly of the 10 edge portion 102. The edge portions 104, 108 are arranged inwardly of the edge portions 103, 105, 107, 109. The edge portions 103, 105 are spaced from each other 15 at their inner ends. The edge portions 107 and 109 are spaced from each other at their inner ends. The other side edge of the edge portion 104 is formed with spaced inverted V-shape cut-outs 111, 112 and 113 and the said other edge is formed with a straight edge portion 114, endwise aligned edge portions 115, 116, 117 and 20 118 of greater length than and arranged outwardly relative to edge portion 114, oppositely inclined edge portions 119, 120, oppositely inclined edge portions 121, 122 merging into each other at their inner ends, oppositely inclined edge portions 25 123, 124 merging into each other at their inner ends and oppositely inclined edge portions 125, 126 merging into each other at their inner ends. The inclined edge portions merge into the edge portions 115 to 118 inclusive. The edge portion 30 119 merges into the inner end of edge portion 114. The edge portion 120 merges into the end edge 127 of blank 101. The outer end of edge portions 102 and 114 merges into the other end edge 128 of blank 101. The blank 101 is formed 35 with portions 129, 130, 131, 132 and 133 which are termed respectively an oblong side part, a rectangular part; a rectangular portion, a rectangular part and a rectangular portion. The rectangular parts are arranged in spaced relation. 40 The rectangular portions are arranged in spaced relation and one thereof is disposed between the rectangular parts. The portion 130 extends at its ends beyond the ends of the portion 129. The portions 131, 133 extend beyond one end of the portions 45 130, 132. That end of the portion 131 as well as the portion 133 which extends beyond the ends of the portions 130, 132 is of tapered form.

The blank 101 is formed with transverse scores 134, 135, 136 and 137 arranged in parallel spaced 50 relation, a lengthwise disposed score 138 which extends from one end of the score 134 to the end edge 127 and which is arranged in proximity to the end edges 115 to 118 inclusive. The score 134 is arranged in proximity to end edge 55 128. The portion 130 in proximity to edge portions 103, 105 is formed with a pair of oppositely inclined scores 139, 140 which are arranged in close spaced relation at their inner ends and have their outer ends terminate respectively in 60 one end of the scores 134, 135. The portion 132 in proximity to edge portions 107, 108 is formed with a pair of oppositely inclined scores 141, 142 having their inner ends arranged in spaced 65 relation and their outer ends merging respectively in the scores 136, 137. The portion 131 is formed with a transverse score 143 which merges into the outer ends of the scores 140, 141 and into the score 143. The portion 133 is formed with a transverse score 144 which at its inner end 70 merges into score 142 and its outer end terminates in score 131. The portions 131, 133 are provided with transverse scores 145, 146 respectively arranged in proximity to edge portions 106, 110 respectively. The portion 131 is formed with two 75

pairs of slits, one pair being indicated at 147 and the other at 148. The pair of slits 147 provide the slits 86, 88. The pair of slits 148 provide the slits 87, 89.

- 5 The portions 138, 132 are formed with diagonally extending scores 149, 150 which provide the bends 82, 83 respectively. That part of blank 101 between score 134 and end edge 128 provides a flap 94. The parts of blank 101 extend outwardly from the score 138 providing the flap 75. The parts of blank 101 which extend outwardly from the scores 136, 140 provide the flaps 78, 79. The part of blank 101 extending outwardly from the scores 141, 142 provides the flaps 80, 81. The parts of blank 101 between the scores 136, 138, 139 and 140 provide the wall 71. The part of blank 101 between the scores 138, 135, 136 and 143 provides a wall 72. That part of the blank 101 between the scores 136, 137, 138, 141 and 142 provides the wall 73. That part of the blank 101 between the scores 137, 138, 144 and end edge 128 provides the wall 74. The top edges of the walls 71, 73 are provided by the scores 138 to 142. The top edges of the walls 72, 74 are provided with the scores 143, 144. The parts of blank 101 which extend outwardly from the scores 145, 146 provide the flaps 85, 81. The blank 101 is formed with slits 151, 152, 153 which extend inwardly from the inner ends of the edge portions 105, 107, 109 to the score 143 and score 144 to provide for the lid sections being free of the flanges 79, 80 and 81.

Referring to Figures 16 to 20 which discloses a modified form of folding box 154, the latter including a body section 155 and a bottom section 156. The body section 155 is of the same construction as body section 69 with this exception that one of the lid sections is not provided with the slits 86 to 88 inclusive, that the walls of the body section 155 are of the same height and that the flaps carried by two of the walls of body section 155 are not oppositely inclined. Otherwise than that as stated the body section 155 will be of the same form and construction as body section 69. The bottom section 156 is of the same form as any one of the bottom sections heretofore referred to. Body section 155 includes the walls 156a, 157, 158, 159, the lid sections 160, 161 which extend from the walls 157, 159. The pair of spaced flaps on the wall 156a are indicated at 162. The pair of spaced flaps on the wall 158 are indicated at 163. The flaps on the lid sections 160, 161 are indicated at 164. The inwardly extending flaps at the bottom of the walls are designated 165. The diagonal bends in body section 155 are indicated at 166. As before stated, the box 154 is of the same construction as the box 68 with this exception that the lid sections are not slitted and the walls 156a and 158 do not have oppositely inclined top edges but straight edges whereby the flaps 162, 163 will not be disposed at an inclination.

The diagonal bend in the bottom section 156 is indicated at 167. The box 154 is closed in the same manner as the box 68 but a lid section does not engage with the flap 162 or flap 163 as is shown in connection with box 68. The flap of box 154 corresponds to flap 94 of box 68, indicated at 166a.

70 Figure 21 illustrates a blank 168 which is of the same form as the blank 101 with this exception that blank 168 is not provided with the pairs of slits 147, 148 as are formed in blank 101. The blank 168 is not provided with the inclined scores 138 to 142 as are formed in the blank 101. In

lieu of forming in the blank 168 the scores 136 to 142 like the blank 101 is provided with, the blank 168 substitutes for such scores an elongated score 169 which extends from a transverse score 170 to the end edge 171 of blank 168. Otherwise than that as stated the blank 168 will be the same as the blank 101. The part of blank 168 which provides the wall 158 and a flap 165 and flap 162 is designated 172. The part of blank 168 which provides the wall 157 with the flap 166, 10 a lid section and a flap 164 is designated 173. The part of blank 168 which provides the wall 156 with the flaps 163 and 165 is indicated at 174. The part of blank 168 which provides the wall 159 with a lid section, a flap 164 and a flap 165 is 15 indicated at 175. The other transverse scores of the blank 168 are indicated at 176, 177, 178. The slits in blank 168 are indicated at 179. The lengthwise extending score in blank 168 which is disposed in parallel spaced relation to and is of 20 the same length as score 169 is indicated at 180. The scores in blank 168 which provide the bends for the flaps 164 are designated 181.

Referring to Figures 22 to 25 a modified form of box 182 is shown and which is of the open top 25 type. The box 182 includes a body section 183 and a bottom section 184. The body section 183 is constructed in the same manner as the body section 1 of the box shown in Figure 1 with this exception that the body section 183 is not provided 30 with oppositely extending lid sections. Otherwise than that as stated, the construction of body section 183 will be the same as body section 1. The construction of bottom section 184 is the same as bottom section 70 which forms an element of the 35 box shown in Figure 1. The walls of body section 183 are indicated at 185, 186, 187 and 188. The walls 185, 187 are provided with inturned flaps 189, 190 which are similar to flaps 9 and 10 respectively of body section 1. The diagonal 40 bends of body section 183 are indicated at 191. The diagonal bend in bottom section 184 is indicated at 192.

Figure 26 illustrates a blank 193 from which the body section 183 is set up. The blank 193 is formed from a web of suitable material such as cardboard. Blank 193 has one lengthwise edge provided with the edge portions 194, 195, 196, 197 and 198. The edge portions 194, 196, 198 are arranged in endwise alignment. The edge portions 198, 197 are arranged outwardly with respect to the edge portions 194, 196 and 198. The other lengthwise edge of the blank 193 is formed with edge portions 199, 200, 201, 202 and 203. The edge portions 200 to 203 are spaced from each other at their inner ends. The edge portion 199 is arranged inwardly with respect to the edge portions 200 to 203. The blank 193 is formed with a score 204 extending from edge portion 194 to edge portion 196 and aligning with 50 such edge portions. The blank 193 is formed with a score 205 which extends from edge portion 196 to edge portion 198 and aligns with such edge portions and further endwise aligns with the score 204. The blank 193 is formed with transversely extending spaced parallel scores 206, 207, 208, 209. The blank 193 is formed with portions 210, 211, 212, 213 and 214. The portions 211 and 213 are of greater length than the portions 210, 212 and 214. These latter portions are of the 55 same length. The portions 211 and 213 extend outwardly from the edge portions 194, 196 and 198. These latter provide one end of the portions 194, 196, 198. The projecting part of the portion 211 is formed with end edges 215, 216 end- 70 75

wise aligning with the scores 206, 207. The projecting part of the portion 213 is formed with end edges 217, 218 which align with the scores 208, 209. The portions 211, 213 are scored diagonally as at 219, 220 respectively which provide the bends for the body section 183. The ends of the score 204 merge into one end of the scores 206, 207. The end of the score 205 merges into one end of the scores 208, 209. The blank 193 is provided with a lengthwise extending disposed score 221 which extends from the other end of the score 206 to the end edge 222 of the blank 193. The score 220 aligns with the edge portion 199 and is spaced inwardly of the edge portions 200, 201. That part of blank 193 extending from score 206 to the end edge 223 of blank 193 provides the flap 224 of the body section 183. That part of blank 193 between the scores 204, 206, 207, 221 provides the wall 187. That part of the blank 193 between edge portion 196, scores 207, 208 and 221 provide the wall 188. That part of the blank 193 between the scores 205, 208 and 221 provides the wall 185. That part of blank 198, end edge 222 and scores 208, 222 provides the wall 186.

The parts of the blank 193 which extend outwardly from score 221 to the edge portions 200, 201, 202 and 203 form the flaps 225 at the lower ends of the walls of body section 183. The parts of the blank 193 which extend from the scores 204, 205 to the edge portions 195, 197 form the flaps 189, 190 of the body section 183.

One of the essential advantages of the several embodiments of the invention as illustrated and described resides in the providing of the body section of each embodiment with inherent means to maintain it in extended open position, or in other words, when such section is extended to open position it is prevented from collapsing which in turn will prevent the folding of the bottom section. The inherent means to obtain the advantage aforesaid resides in positioning flaps in an inwardly extended related position with respect to the top of opposed walls of a body section, such as shown in Figures 1, 6, 11, 16 and 22. As to Figures 1 and 6 the bends upon which the body section is folded not only extend diagonally of a pair of opposed walls but also diagonally of the flaps 9, 10 whereby when these latter are in the position as shown in Figures 1 and 6 the body section is prevented from collapsing or folding. As to Figures 11 and 16, each body section shown thereby includes two pairs of flaps at the top of opposed walls, one flap of each pair being formed with a diagonal continuation of one of the bends upon which the body section is folded. Two of the flaps shown in Figure 11 and in Figure 16 will function in the same manner as the flaps forming parts of the body sections of the boxes shown in Figures 1 and 6. As to Figure 22 the flaps 189, 190 are formed with diagonal continuations of the bends 191 and will function similar to the flaps 9, 10.

What I claim is:—

1. In a folding box, a body section including pairs of walls, the walls of each pair being arranged in opposed relation, the walls of one pair being provided at their upper ends with oppositely foldable flaps, the walls of the other pair being provided at their upper ends with oppositely foldable lid sections, said body section being formed

with means to constitute a pair of oppositely extending continuous bends upon which the body section is foldable and extendible, said means being disposed diagonally of that pair of walls provided with the flaps and diagonally of the flaps, a foldable bottom section connected to said body section, each of said lid sections being oppositely slotted to provide bendable parts coacting with each other and with the flaps, when these latter are folded inwardly, for releasably securing the lid sections in closed position relative to said body section.

2. In a foldable box of that type including a foldable and extendible body portion having an integral closure for its top, a one-piece web providing said body portion and closure, said web consisting of an oblong side part having upper and lower ends, a pair of like parts of rectangular contour arranged in spaced relation and each having upper and lower ends, said side part merging at its inner side into the outer side of one of said rectangular parts and having its ends spaced from the ends of said side of the said rectangular part, a pair of like portions of rectangular contour arranged in spaced relation, of greater length than the said rectangular parts and each having upper and lower ends, one of said rectangular portions merging intermediate the ends of one side thereof into the inner side of one of the said rectangular parts intermediate the ends of the latter, the other side of the said rectangular portion intermediate the ends thereof merging into one side of the other of said rectangular parts intermediate the ends of the latter, the other of the said rectangular portions merging at its inner side intermediate the ends thereof into the other side of the said other rectangular part intermediate the ends of the latter, the said rectangular portions extending upwardly beyond the upper ends of the said rectangular parts, said web being formed respectively with spaced upper and lower horizontally disposed scores aligning at one end with the ends of said oblong part and extending from such ends to the outer side edge of the said other rectangular portion, lengthwise scores at right-angles to the other scores and arranged between said rectangular portions and parts, and diagonally disposed scores, each being formed in a rectangular part and extending from said horizontal lower score to the upper end of such part to a point on the latter in spaced relation to a rectangular portion.

3. The invention as set forth in claim 2 having each of said rectangular parts formed with a slit extending from the upper end edge of said part to said upper score.

4. The invention as set forth in claim 2 having each of said rectangular portions formed with a pair of oppositely extending horizontal slits opening at the side edges thereof above said rectangular parts.

5. The invention as set forth in claim 2 having each of said rectangular portions formed with a pair of oppositely extending horizontal slits opening at the side edges thereof above said rectangular parts, the slits of one of said rectangular portions being arranged below the slits of the other rectangular portion.
